LOWER CYLINDER FOR DIESEL PILE DRIVER

Christopher William Bermingham, Dundas, Ontario, and
Fred Kirkpatrick, Waterdown, Ontario, Canada, as
signors to Berminghammer Corporation Limited,
Hamilton, Ontario, Canada

Filed June 30, 1969, Ser. No. 17,958

Claims priority, application Canada June 28, 1969

Term of patent 14 years

Int. Cl. D15—04

U.S. Cl. D41—1

FIG. 1

FIG. 2

FIG. 1 is an isometric view from above of a lower cylinder for diesel pile driver; and

FIG. 2 is an isometric view from below of the lower cylinder illustrated in FIG. 1, the cylinder being viewed in FIG. 2 in the direction substantially opposite to the direction in which the cylinder is viewed in FIG. 1.

We claim:

The ornamental design for a lower cylinder for diesel pile driver, as shown.
